United States Patent Office.

EDWIN C. CLEVELAND, OF WORCESTER, MASSACHUSETTS.

Design No. 3,768, dated November 30, 1869.

DESIGN FOR THE FRAME OF A CARDING-MACHINE.

The Schedule referred to in these Letters Patent and making part of the same.

To all persons to whom these presents shall come:

Be it known that I, EDWIN C. CLEVELAND, of the city and county of Worcester, and State of Massachusetts, have originated and Designed a new and useful Pattern for Frames to Carding-Machines, of which the following is a full, clear, and exact description, reference being had to the accompanying drawing, making part of this specification.

Figure 1 is a side elevation of a card-frame, to be cast in iron in one piece, two of which are required for a machine.

The body of the frame is made of suitable thickness, to correspond to the size and weight of other portions of the machine. Suitable mouldings surround the outer edges, and the large holes or openings in the frame, and are made to project a sufficient width to give the required strength.

The openings marked A A are fitted with thin panels, which can be cast in or left out, as may be desired.

The large openings marked B B can be left open or be fitted with panels or doors, either of wood or metal.

Claim.

What I claim as my invention, and desire to secure by Letters Patent, is—

The design or form and arrangement of patterns for card-frames, herein set forth.

EDWIN C. CLEVELAND.
